US00D968691S

(12) **United States Design Patent** (10) Patent No.: **US D968,691 S**
 Cheung et al. (45) Date of Patent: ** Nov. 1, 2022

(54) **VAPORIZER CARTRIDGE**

- (71) Applicant: **JUUL Labs, Inc.**, San Francisco, CA (US)
- (72) Inventors: **Brandon Cheung**, San Francisco, CA (US); **Carlos A. Dominguez**, San Pablo, CA (US); **Dylan E. Entelis**, Los Angeles, CA (US); **Matthew J. Malone**, Los Angeles, CA (US); **James Monsee**, San Francisco, CA (US); **Zachary T. Scott**, Oakland, CA (US); **John Travis Wettrath**, San Francisco, CA (US)
- (73) Assignee: **JUUL Labs, Inc.**, San Francisco, CA (US)

(**) Term: **15 Years**(21) Appl. No.: **29/825,822**(22) Filed: **Feb. 4, 2022****Related U.S. Application Data**

- (63) Continuation of application No. 29/713,288, filed on Nov. 14, 2019, now Pat. No. Des. 943,158.
- (51) **LOC (13) Cl.** **27-02**
- (52) **U.S. Cl.** **USPC** **D27/162**
